OSCILLATING DOCTOR KNIFE BAR AND CUTTING ANGLE ADJUSTMENT

Albert M. Fischer, Dowagiac, Mich., assignor to Davenport Machine and Foundry Company, Davenport, Iowa, a corporation of Iowa

Application March 10, 1955, Serial No. 493,327

4 Claims. (Cl. 15—256.5)

The present invention relates to doctor knives for moving surfaces and is more particularly directed to an apparatus for adjusting the cutting angle and depth of cut of oscillating doctor knives, and to a means for the simple accomplishment of coordinated oscillation while the surface served is in motion.

The art has long recognized that present day doctor-knife assemblies are inefficient in their operation when the material *per se* is changed from those conditions for which the cutting angle of the knife assembly is initially set or designed to operate under. In such instances where the optimum cutting angle must be determined by trial and error the dryer apparatus, for example, must be shut down while the cutting angle is being adjusted. Further, when the knife blade becomes dull most known assemblies require the lengthy process of sharpening or honing or the replacement of the dull blade. The cutting angle available for a single assembly is limited by the inherent design features of the particular doctor knife assembly. Therefore, as different materials are fed, these being dictated by production pressures, the efficiency of the doctor knife may be reduced because variations in cutting angle are not readily available. Further, when the blade becomes worn, the thermal efficiency of the dryer is reduced due to incomplete removal of material from the drum and in instances of maladjustment scoring of the surfaces served frequently occurs. Present day known designs do not provide a structure capable of prolonging the life of a blade by changing its cutting angle during operation.

In order to reduce wear to a blade or damage to a surface due to uneven or excess pressures, present day construction of doctor knife apparatus generally has provided for an oscillating movement of the entire doctor knife assembly transverse the face of the drum paralleling the axis of the drum where, for example, dryer drum surfaces are being served. That is to say in some designs the knife, the knife bar, the knife bar support, the support axles, the bearings, and even the bearing supports have been designed to oscillate with the knife. Such a system has a relatively large power requirement. Minimization of these relatively large power requirements of drum and oscillating apparatus has long been sought. Further, the equipment and mechanism for accomplishing such movement is expensive to produce, install, maintain and repair. In such oscillating systems where the entire assembly oscillates the oscillation frequently damages the alignment of the equipment with which it is associated. No known doctor knives, either oscillating or stationary, have been designed to change the cutting angle or angle of attack of the knife blade to a served surface, for example, a rotating drum, during continuous operation. Some adjustment of cutting or attack angle is required in all doctor knives, whether they serve a planar or cylindrical surface. In the previously known doctor knives, the equipment must be stopped and the operation shut down in order to change the cutting angle of the blade. Since

2

adjustments cannot be made during operation the thermal efficiency of the dryer surface is impaired and damage to the surface served often results from unavoidable changes during service. It will be seen that the novel construction hereinafter described avoids these numerous difficulties encountered by presently known doctoring knives.

Further deficiencies are found in, for example, double drum dryers of the present day construction, wherein end dams are utilized to maintain the material within the confines of the working surface. These dams are maintained in position by end dam pressure spindles. The pressure of the spindles tends to force the dryer frames out of alignment and cause damage to bearings, knife bar bearings, et cetera. Spacers and bracing structures are normally provided below the drum to prevent misalignment. These, however, are not completely satisfactory. No known doctor knife assemblies assist in providing bolstering support.

Therefore, an object of the present invention is to provide an oscillating doctor knife assembly which will oscillate only the knife bar with the knife blade.

Another object of the present invention is to provide a simple oscillating doctor knife construction which is operationally strong and durable.

Another object of the present invention is to provide an oscillating doctor knife assembly which will permit the quick and easy selection of the most advantageous knife blade cutting angle while the drying, gauging or smoothing operation of the knife is continued and which will permit continuous oscillation even during the change in cutting angles.

A further object of the present invention is to provide an oscillating doctor knife which is adjustable in its angle of attack without interruption of continuous operation.

A still further object of the present invention is to provide an economically fabricated doctor knife construction, adaptable to a variety of planar or cylindrical surfaces and materials, which is easily maintained and repaired.

A further object is to provide a doctor knife construction having as a result of reduced pressure of the doctor knife a reduction of power requirement to the moving surfaces served.

Another object of the present invention is to provide a knife bar assembly which will serve as a tie rod and assist in counteracting the outward thrust and stresses of the end dam pressure spindles in, for example, a single or multiple drum dryer.

Another object is to provide a knife bar assembly which assures thermal efficiency of the surface served.

A still further object of the present invention is to provide an oscillating doctor knife which can be adjusted in cutting angle approach to present at all times a sharp, well-defined blade point to the served surface and thus prolong the serviceability of the blade, during continuous operation of the knife assembly.

These and other objects will become apparent to those skilled in the art as the description of the present invention proceeds.

GENERAL DESCRIPTION

The present invention provides a doctor knife apparatus having concentric shafting, and an outer cylindrical case forming a knife bar. The knife bar or outer cylindrical case is displaced from concentricity with the concentric shafting by a pair of eccentrics mounted on an outer or main shaft. The main shaft has an oscillating drive shaft concentrically mounted within one end thereof to provide oscillating motion to the outer eccentrically rotatable mounted cylindrical case or knife bar. The linkage between the drive shaft and case through the main shaft is accomplished by a drive pin. The cylindrical case or knife bar carries a knife clamping plate and a doctor blade. Means associated with the outer eccentrically rotatably mounted cylindrical case or knife bar are provided to rotate the blade carrying case about the eccentrics. Additional means are provided to rotate the main shaft and associated eccentrics independently of any rotation in the eccentrically mounted cylindrical case.

In the preferred embodiment of the present invention, when, for example, the surface served is a rotating drum, a doctor knife assembly is provided offset from the drum face and extending longitudinally across the convex face of the drum parallel to the axis of rotation of the drum. The doctor knife assembly or apparatus comprises a pair of bearing mounts or bearing supports mounted on, or attached to, the housing or dryer frame; bearings mounted in the bearing mounts; a main shaft rotatably mounted within the bearings and extending across the face of the drum parallel with the axis of rotation of the drum, at least one end of the main shaft being tubular and concentrically bored to receive and journal an oscillating drive shaft; and the main shaft being longitudinally slotted near the inner end of the concentric longitudinal bore to provide a pair of guideways through the opposite walls of the main shaft; a drive pin penetrating said drive shaft projecting outwardly therefrom through the slots provided therein and beyond the outer circumference of the main shaft; a grooved receiving ring fixed against longitudinal movement in the cylindrical case being in clearance relationship around the main shaft and having the drive pin of the drive shaft inserted in the groove of the ring for causing axial movement of the knife case in coordination with the oscillation of the drive shaft; and a pair of eccentrics keyed on the main shaft near each end thereof for movement with the main shaft between the bearings of the main shaft and outboard of the longitudinal slots in the main shaft. Concentrically mounted over the keyed eccentrics in rotatable relation thereto is a cylindrical case or knife bar tube having a tangential external ledge for attachment of a knife clamp plate and a doctor knife blade. Hubbed arms are adjustably secured to the cylindrical case or sleeve at either end thereof, the arms being provided with pivotal levers depending from the hubs at either end of the doctor knife assembly. Shoulders integral with the cylindrical case inboard of said hubs and split rings outboard of said hubs are provided to maintain said hub and associated arms in aligned axial relation

with said eccentrically mounted sleeve or knife bar. Independently adjustable means are provided on the end of each of the depending arms for adjustably rotating the lever arms to cause resulting rotation of the cylindrical case or knife bar about the axis of the eccentrics.

5 A bearing housing at one end of the main shaft is provided with a worm and worm gear. The worm gear is keyed to the main shaft. A worm is provided with a hand wheel. Rotation of the main shaft and eccentrics secured thereon is accomplished by manual operation of the hand wheel. It will be understood that automatic drives can be substituted for the manual operation.

10 A reciprocating drive attached to the drive shaft at one end oscillates the doctor blade as indicated.

15 It will thus be seen that an apparatus is provided which during the operation may be adjusted as to cutting angle and which is continually oscillated without interruption of continuous process operation.

SPECIFIC DESCRIPTION

20 Referring with more particularity to the drawings a moving surface shown as a rotating drum dryer 11 is shown in Figure 1 having a drum 12 rotatable about an axis. In Figure 6 a double drum dryer 13 is illustrated. 25 The axles 14 of the drums 15 are mounted in bearings within a frame 16 having end dams 17 and 18. The end dams 17 and 18 laterally confine the material fed between the drums 15 (Figure 6). Mounted on the frame 16 are 30 a pair of bearing supports 19 and 20, respectively, each provided with bearing receiving means. Within each bearing support 19 and 20 are bearings 22 and 23. One of said bearing supports 20 comprises a combination bearing and worm gear housing 24. The purpose of the worm gear drive will be more fully understood as the description proceeds.

35 A main shaft 25 is rotatably mounted in the bearings 19 and 20. On one end of the main shaft 25 and within the worm gear housing 24 is keyed a worm gear 26. Each end of the main shaft 25 is secured outboard of the bearing supports 19 and 20 thus preventing the shaft from shifting longitudinally. Various securing means may be employed, the simplest being split rings 27 and 28 retained in suitable grooves in the main shaft 25. The worm gear end of the main shaft 25 is tubular, being provided with a concentric bore 29 extending longitudinally into the main shaft 25. Near the extreme inner end of the bore 29, the main shaft 25 is provided with a pair of longitudinal slots 30 and 31 through the wall of the main shaft 25 communicating the main shaft outer circumference with the concentric bore 29.

40 Concentrically mounted within the bore 29 is an oscillating drive shaft 32. The drive shaft 32 is reciprocatingly journaled in the bore 29. At the inner end 33 of the drive shaft 32 is a drive pin 34 secured through the drive shaft 32. The pin 34 extends radially outward from the drive shaft 32 into and through the elongate slots 30 and 31 through the wall of the main shaft 25. The drive pin 34, attached to the drive shaft 32, can thus float reciprocatingly in the slots 30 and 31. A 45 grooved receiving ring 35 receives the extensions of the pin 34 where it extends beyond the outer circumference of the main shaft 25. The drive pin 34 rides in close tolerance in the groove 36 of the receiving ring 35 and the receiving ring 35 responds to any reciprocatory movement of the drive shaft 32. In the preferred construction of the grooved receiver ring 35, the groove 36 is defined by the internal shoulder of the ring 35 and an abutting annulus 35a having an inside diameter smaller than the diameter of groove 36 so as to retain the drive pin 34 in the groove 36. The receiving ring 35 is a hollow cylinder and is in clearance relationship with the main shaft 25. The importance of this receiving ring 35 will become increasingly apparent as the description proceeds.

50 A pair of eccentrics 37 and 38 are secured as by a key 37a to the main shaft 25 inboard of the end dams 17

and 18 and outwardly of the slots 30 and 31 in the main shaft 25. The eccentrics 37 and 38 are in fact cylinders having an offset axis from the axis of the drive shaft 32.

A cylindrical case or knife bar sleeve 39 is concentrically mounted on the eccentrics 37 and 38 for rotatable movement thereover and in sliding reciprocating motion therewith. The cylindrical case 39 has a tangential flanged ledge 40 for mounting a doctor knife blade 41 and a doctor clamp plate 42 thereon. The blade 41 is preferably secured by the clamp plate 42 and the thumb screws 43 are provided for alignment. Bolts 44 through the flange 40 and the blade 41 draw the blade 41 securely against a machined step 45 in the flanged ledge or shoe 40. Thus, the cylindrical case or sleeve 39 is rotatable on the eccentrics 37 and 38 and carries a blade mounting ledge 40 to which the blade 41 is attached. On the inside of the cylindrical case 39 a shoulder 46 is provided against which the receiver ring 35 is positioned. A spaced annular groove 47 is provided in the inside of the cylindrical case 39 for accommodating a snap-ring 48 against which the other side of the receiver ring 35 abuts. Thus, the cylindrical case 39 may be rotated about the receiver ring 35, but the case 39 is moved longitudinally as the receiver ring 35 is oscillated by the drive pin 34 in response to longitudinal movement of the drive shaft 25.

While the receiver ring 35 has been described as rotatable within the shoulder 46 and the snap-ring 48, it may also be held tightly therebetween and prevented from movement independent thereof. The annular receiving ring groove 36 thus becomes the surface within which the pin 34 rotates. The reciprocation of the knife bar or case 39 still is controlled by the reciprocation of the pin 34 with the drive shaft 32.

At each end of the cylindrical case 39 are collar-like brackets or hubs 49 and 50 rotatably and adjustably attached to the cylindrical case or knife bar 39. The adjustable attachment is accomplished by means of set pins 51 and 52, each having an eye 53 and 54 at their outer extremity. The brackets or hubs 49 and 50 accommodate the set pins 51 and 52 which lock the brackets 49 and 50 in a desired position on the ends of the cylindrical case 39. Clearance is provided between the brackets 49 and 50 and the bearing supports 19 and 20 so that as the cylindrical case or knife bar 39 is oscillated the moving brackets 49 and 50 do not contact any part of the frame 16 or the bearing supports 19 and 20. Lateral movement of the hubs 49 and 50 along the cylindrical case 39 is restricted by annular shoulders 49a and 50a on the case 39 and split rings 55 and 56 seated in annular grooves 57 and 58 in the surface of the case 39 near the ends of the case 39.

Arms 59 and 60 in the nature of levers depend from the brackets or hubs 49 and 50. Knife pressure adjusting means 61 and 62 mechanically and linkedly extend to adjustably engage the lever arms 59 and 60. The movement of the adjusting screws 61 and 62 causes arcuate movement of the levers 59 and 60 and corresponding rotational movement of the case 39. The arms 59 and 60, in the nature of levers, are pivotal where they attach to the brackets 49 and 50. By thus pivoting the arms 59 and 60 rockably from the brackets 49 and 50, rotational adjustment of the case 39 is provided and the pivoted arms 59 and 60 can clear any associated apparatus in the manner of a pivotal link. The knife pressure adjusting screws 61 and 62 are actuated by handwheels 63 and 64 rotatable in fixedly mounted blocks 63a and 64a, correspondingly left and right as shown in Figure 4.

Internally threaded actuating members 65 and 66 are threaded onto the knife pressure adjusting screws 61 and 62, and are pivotally connected to the depending ends of the arms 59 and 60 through unique pivotal blocks 67 and 68, respectively. Then blocks 67 and 68 are pivotally mounted at one end to the arms 59 and 60 and rotatably connected thereto in the manner of a universal.

The rotatable connector is further right angularly and rotationally mounted in the pivot blocks 67 and 68 as clearly shown in Figure 1. The mechanism shown in Figure 4 provides a suitable steady rest or guide against any objectionable rotational movement. Element 65 is shown as an internally threaded sleeve having an outer sleeve 65a slidably mounted thereover said sleeve 65a having a cylindrical projection 65b extending right angularly therefrom journaling through arm 67. This novel arrangement provides a universal action maintaining each main part in proper alignment yet permitting angular movement of the parts. Thus arm 59 can swing in an arc in response to lineal movement of block 65 along screen 61. The universal coupling provides in accordance with the mechanical requirements of the respective member the movement of internally threaded members 67 and 68 along screw 61 and 62 permitting a swinging or arcing movement of arms 59 and 60 without binding members 67 and 68 to screws 61 and 62 respectively.

Assuming the set pins 51 and 52 to be locked to the case 39, rotation of the handwheels 63 and 64 causes corresponding lateral movement in the actuating members 65 and 66 and through the linkage with the universal joint arcuate movement of the arms 59 and 60. The arms 59 and 60 are moved causing rotation of the brackets 49 and 50 and subsequent rotation of the case 39.

The bearing housing 20 comprising one of the bearing supports has therein a worm 69. The worm 69 is in operable engagement with the worm gear 26. The worm gear 26 is keyed to the main shaft 25. A worm handwheel 71 is operably attached to the shaft of worm 69. The housing 24 of the worm 69 and associated bearings 72, as necessary, are provided in the bearing support 24. As the worm 69 is rotated the worm gear 26 is actuated, thus rotating the main shaft 25 and the eccentrics 37 and 38 mounted thereon.

A reciprocating drive device 73 is provided outboard of the bearing support 20 and is directly connected to the drive shaft 32. The reciprocating device 73 is aligned with the drive shaft 32. While the drive device 73 illustrated, consisting of a fluid operated cylinder, represents one satisfactory means of accomplishing positive reciprocation of the drive shaft 32, other equivalent mechanical expedients well known in the art are intended to be descriptively included such as rack and pinion, hydraulic and pneumatic double acting pistons, and various cam, screw gearing and eccentric arrangements and reversible direct electric drives. In cooperation with the reciprocating drive device 73, timing means are intended to be included for varying the frequency of oscillation as desired. The hydraulic lines 77 and 78 supplying power to the drive device 73 are indicated in Figure 1.

Operation

In the operation of the oscillating knife bar and cutting angle adjustment of the present invention, the worm handwheel 71 is rotated to adjust the cutting angle of the doctor knife blade 41 to the desired angle for the particular material to be removed from the cylindrical or planar served surface 74. The worm handwheel 71 operates the worm gear 26 which is keyed or otherwise secured to the main shaft 25, thus rotating the main shaft 25. This rotation of the main shaft 25 will cause corresponding rotation of the keyed eccentrics 37 and 38. Rotation of the eccentrics 37 and 38 on the axis of the main shaft 25 will change the angular relation between the main shaft 25 and the cylindrical case 39 carrying the knife blade 41. The angular relationship as between blade 41 and served surface 74 will be altered correspondingly but the action of the eccentrics 37 and 38 is predominantly cam-like in nature serving to back off from or approach the blade 41 to the surface 74 served. The action of eccentrics either backs off the blade 41 in relation to the surface served 74 or moves the blade 41 into closer relationship with the served surface 74. Position

B in Figure 10 demonstrates this adjustment on an exaggerated scale.

The set pin 51 or 52 in one of the brackets 49 or 50 is withdrawn. The other set pin 51 or 52 is left in its locked position in the cylindrical case 39 and through the bracket 49 or 50. The screw 61 or 62 engaging the arm 59 or 60 is rotated by means of handwheel 63 or 64 so as to rotate the cylindrical case 39 by arcuately moving the bracket 49 or 50 which is still locked into engagement with the case 39. This movement pivots the case 39 and the associated knife blade 41 into or out of engagement with the cylindrical or planar working surface and thus changes the attack angle of the blade 41 when coordinated with the action of the eccentrics 37 and 38. When drum dryers 15 are served, this compound adjustment results in a variety of cutting angles being made available at the drum surface. The pressure of the blade 41 on the surface is controlled primarily by the rotation of the case 39 and these adjustments are made without interruption of movement in the drum dryers or the reciprocation of the blade 41. The other handwheel 63 or 64 is then rotated in the same direction until its set pin 51 or 52 which was withdrawn drops into a hole 75 or 76 provided in the case or knife bar 39. The set pin holes 75 and 76 are in alignment to that the motion in both screws is thus coordinated. From this position the handwheels 63 and 64 rotating the case 39 are used to regulate the pressure forcing the knife blade 41 against the drum surface 74.

The reciprocating drive device 73 is energized causing reciprocation of the drive shaft 32. The frequency of oscillation is adjusted as desired by timing means not illustrated. This reciprocation of the drive shaft 32 and its associated drive pin 34 causes corresponding longitudinal and axially oscillatory movement of the cylindrical case 39 and its associated blade 41. This reciprocating linkage is accomplished through the drive pin 34 reciprocating in the slots 30 and 31 through the main shaft 25 and the connection of the drive pin 34 in the groove 36 of the longitudinally fixed receiving ring 35. The drum 12 (where the surface doctored is cylindrical) is now rotated and a slurry is fed, for example, to the dryer.

If it is desired to change the cutting angle of the blade 41 during operation, it is necessary to operate the handwheel 71 to cause eccentric blade displacement and constant surface contact while simultaneously operating handwheels 63 and 64 to revolve the case 39 and associated blade 41 on the eccentrics 37 and 38, as indicated, to maintain contact pressure. It will be understood that though manual means for this adjustment have been specifically described automatic adjustment as by springs, hydraulic, or electrical actuation may be inserted without a departure from my structure.

In Figures 7, 8, 9, and 10 the effect of the blade adjusting structure on the blade 41 is indicated. In Figure 7 the blade 41 is shown in angular point contact with a cylindrical drum surface 74. The line X—X' is a tangent to the surface at the point of blade contact. The lower side of the blade Y—Y' establishes an intersecting plane through the point. In Figure 8 an exaggerated view of a worn blade 41 is shown engaged with the surface 74 of the drum 12. The wearing of the blade has created a new surface W—W' and the point of contact of the blade has been destroyed. In Figure 9 it is seen that by increasing the original cutting angle a new edge at the point of contact with the drum has been established as between the wear plane W—W' and the plane X—X' tangential to the cylindrical drum surface 74 through the point. Such adjustments as these necessitate only a slight change of the cutting angle and are accomplished with the herein described structure without operational interruption. Movement of the eccentrics 37 and 38 by turning the worm handwheel 71, while the structure is still reciprocating, accomplishes the changes indicated with a minimum

amount of inconvenience. As shown in Figure 10 the individual movements comprising the compound movement of a blade 41 are indicated by the phantom line exaggerated positions a and b.

In Figure 6 a double drum dryer 13 is shown to illustrate a double drum installation of a doctor knife in accord with the present invention. Various plural installations are encompassed in the scope of the described structure. With particular reference to the double drum installation (Figure 6) it will be seen that the doctor knife assemblies comprise effective tie rods rendering the entire structure more rigid despite the constant oscillation of the blade 41. The tie-rod effect of the described doctor knife assembly also counteracts the pressures on the end dams 17 and 18 tending to spread the frame 16.

It will be seen that the change of angle can be made without stopping the drum or the oscillating knife bar. Similarly, depth of cut is, where desired, independently changed without interrupting continuous process operation. The advantages of such an operation are apparent. Firstly, no cake is built up during adjustment. Secondly, the operation continues without shut-down. Thirdly, an infinite variety of compound adjustments of cutting angle with depth adjustment are possible independent of continuing process operation or associated oscillation.

The described doctor knife apparatus has broad application to all types of operations involving the continuous flow of material such as, for example, yeast, chocolate, pulp, or plastic or semi-plastic material on planar or cylindrical stabilized surfaces. In association with continuous yeast drying equipment of all known types the apparatus described has proved itself to be unusually efficient in minimizing power requirements and avoiding process interruption.

It is thus seen that a novel and highly useful arrangement has been provided which will allow depth and cutting angle adjustment of the doctor blade during operation and a novel system has been provided to continuously oscillate the doctor blade. The apparatus has proved economical to fabricate, simple to install and easy to maintain.

It will be understood that various modifications of my described invention may be made and such modifications are intended to be included in the scope of my hereinafter appended claims, unless the scope of such claims negatives such inclusion.

Having thus described my invention, I claim:

1. In a doctor knife assembly, the combination including: a main shaft paralleling and offset from a served surface, journal means supporting said main shaft; cylindrical eccentric members operably secured to said main shaft in aligned spaced relation thereon; a cylindrical case rotatably mounted over said eccentric members; means within said case securing said shaft to said case for axial movement therewith; means for selectively rotating said shaft on its axis; and a knife support rigidly longitudinally and substantially tangentially mounted on said cylindrical case and having a surface engaging blade attached thereto.

2. In a doctor knife assembly for serving a moving surface, the combination including: a main shaft paralleling and offset from a served surface, said main shaft having a concentric longitudinal bore extending from one end thereof and terminating in a radial longitudinal slotted guideway through the wall of said main shaft; journal means supporting said main shaft; a grooved receiving ring mounted over said main shaft

having a circumferential keyway within the inner surface thereof; a drive shaft journaled within the longitudinal bore of said main shaft; a drive pin insertable through said main shaft guideway and engageable with said circumferentially grooved receiving ring and said drive pin being attached to said drive shaft; a cylindrical

case over said main shaft; and a reciprocating drive axially oscillating said drive shaft and said cylindrical case.

3. In a doctor knife assembly for serving a moving surface, the combination including: a main shaft paralleling and offset from a served surface, said main shaft having a concentric longitudinal bore extending from one end thereof and terminating in a slotted guideway through the wall of said main shaft; journal means supporting said main shaft; cylindrical eccentric members operably secured to said main shaft in spaced relation thereon; a cylindrical case rotatably mounted over said eccentric members; a grooved receiving ring fixed to said case and having the groove thereof in cooperating alignment with the slotted guideway of said main shaft; a drive shaft journaled within the longitudinal bore of said main shaft, said drive shaft having a projection insertable through said main shaft guideway and engageable with said grooved receiving ring; eccentric adjustment means keyed to said main shaft; rotating means adjustably secured to said cylindrical case; a reciprocating drive operably secured to said drive shaft; and a knife support rigidly and substantially tangentially mounted on said cylindrical case having a surface engaging blade attached thereto.

4. In an oscillating doctor knife apparatus, for adjusting a doctor blade to a served surface independently

from the motion of such surface and the oscillation of such blade, the combination including: bearing supports; a partially tubular main shaft in said bearing supports in parallel relation with a served surface and having a longitudinal slot through the tubular wall portion; a drive shaft journaled concentrically in the tubular portion of said main shaft; a pair of eccentrics keyed to said main shaft in spaced relationship; a cylindrical case in close tolerance rotational engagement over said eccentrics and carrying a knife blade; a grooved receiving ring in said case retained by said case from longitudinal movement; a drive pin projecting from said drive shaft through the slot in said main shaft and engaged in the groove of said receiver ring; geared means for rotating the said main shaft and said eccentrics; collar-like brackets lockably engaging the ends of said cylindrical case; lever arms depending from said brackets; actuating means for arcuately moving said lever arms thereby rotating said cylindrical case; set pins locking said brackets to said cylindrical case; and a reciprocating device longitudinally oscillating said drive shaft and said case.
